UNITED STATES PATENT OFFICE

ABRAHAM ASHKENAS, OF BROOKLYN, NEW YORK

WINDOW-DISPLAY FIXTURE

Application filed February 24, 1928. Serial No. 256,622.

This invention relates generally to display fixtures adapted for special use in connection with my improved screen described and claimed in my co-pending application 5 Serial Number 238,806, filed December 9, 1927.

In a general way the object of the instant invention resides in the provision of novel means whereby the utility and the field of use of said screen may be greatly enhanced. 10 In this connection it may be pointed out that while said screen finds its greatest applicability for decorative purposes, the use of my novel and unique fixtures permits the 15 display of goods in conjunction therewith, and thus, attractiveness and silent salesmanship are combined.

Another object of the invention resides in the provision of novel fastening means normally carried by the individual fixture and adapted to removably secure the latter to a 20 standard.

Still another object resides in providing said fastening means with lateral prongs 25 adapted for forceful entry into the walls of a groove in a standard to facilitate the securing of a fixture to said standard.

A further object is to provide fixtures of varying sizes and shapes, for example, 30 brackets, hooks or other supporting devices, each fixture having a tongue or web adapted to cooperate with a groove in a standard to prevent lateral deflection of said fixture therein.

The invention is further featured by novel 35 panel-supporting members adapted to maintain a plurality of standards in spaced relation and to permit the attachment of a selected panel subsequent to the assembling 40 thereof.

With these objects in view, together with others which will appear as the description proceeds, the invention resides in the novel formation, combination and arrangement of 45 parts, all as will be described more fully hereinafter, illustrated in the drawings, and particularly pointed out in the claims.

In said drawings:

Figure 1 is an elevation of my improved 50 screen, with parts broken away, a suggested

arrangement of fixtures being shown as attached to the supporting standards.

Fig. 2 is a transverse sectional view, slightly enlarged, and taken on the line 2—2 of Fig. 1, to depict the arrangement of the 55 panel and its supporting members.

Fig. 3 is a sectional view taken through the base of a fixture to show the co-action between its fastening means and a grooved standard supporting a panel. 60

Fig. 4 is a sectional view of a standard and illustrating the first step in the attachment of a fixture thereto.

Fig. 5 is a similar view but illustrating further progress in the attaching operation. 65

Fig. 6 is a view like unto Fig. 5, but depicting the fixture anchored in a groove and the position of its tongue in said groove.

Fig. 7 is a transverse sectional view, taken substantially on the line 7—7 of Fig. 6. 70

Fig. 8 is a detail view of the fastening means.

Fig. 9 is a plan view of one form of mixture, with its fastening means.

Fig. 10 is a side elevation of another form 75 of fixture.

Fig. 11 is a sectional detail illustrating the fastening means in position for uniting the panel supporting members and standards; and 80

Fig. 12 illustrates an adaptation of certain fixtures cooperating with a standard to provide supporting means therefor.

Referring now more in particular to the accompanying drawings, with special reference to Fig. 1, the numeral 10 denotes a panel supported by top and bottom members 11 and 12 carried by standards 13 and 14, the upper portion of each being preferably octagonal in cross-section and presenting a plurality of radial, longitudinally disposed grooves 15, (see Fig. 3), and it is these grooves, or any selected one of which, that cooperate to secure my novel fixtures to said standard or standards. 85

In said Fig. 1, the fixtures are shown in a suggested arrangement with respect to the screen, and it will be observed that a supporting member 16, in the form of a hook, 90 is attached to said standard 14, while its 95

companion standard 13 carries fixtures 17 and 18, the former presenting a horizontal shelf-like portion upon which may be mounted perfumery bottles, or similar articles, while said fixture 18 is preferably provided with an inclined top portion for the reception of boxed articles, such as confectionery or the like. The particular shape or size of the fixture is not in itself of vital importance, provided, of course, its configuration conforms to the general dimensions and aspects of a screen in order to enhance, rather than detract from its ornamental appearance. It is again reiterated that the screen is made ornamental and attractive in order to beautify a shop window, or the like, and is depended upon to attract the attention of the buyer, and when this is accomplished the fixtures with their particular line of merchandise thereon apprises said buyer of the class of goods handled by the store.

It is also pointed out that said fixtures may be secured to the standards at any desired point within the grooves thereof and hence their decorative features, as combined with a screen, are limited only by the knowledge of the window-dresser.

Attention is now directed to my improved fastening means 19, (see Fig. 8), which comprises a shank portion 20, having one end portion threaded and sharpened to be affixed to the base portion of a selected fixture. The other end of said fastening means 19 is tapered to a point, as indicated at 21, and at the rear thereof are provided laterally disposed prongs 22-23, each presenting sharpened terminals for engagement with the side walls of a groove, as will presently appear.

Said fastening means is similar for each fixture and since the essential cooperative features of the latter, with respect to a standard, are also of the same nature, fixture 16 has been selected and illustrated in the drawings to clearly show the means and method of the attachment of any of the fixtures to a standard. Hence, on consideration of Figs. 6 and 7 it will be observed that the base portion 16^a is provided with a rearwardly disposed tongue or web 24, having a beveled outer face 24^a, and being of a width equal to that of said grooves 15. Each of said fixtures have their basal portions provided with a similar tongue or web.

After said fastening means 19 has been secured to the fixtures, as shown in Fig. 3, the selected fixture 16 is turned to place its base portion 16^a in a horizontal position, as shown in Fig. 4, which position being substantially at right angles to the affixed position of said fixture as shown in Fig. 1, whereupon the forward portion of said fastening means 19 is entered into a selected groove 15 and the point 21 forced into the rear wall of the groove, the lateral prongs

22-23 being alined with the longitudinal axis of said groove. Next said fixture 16 is turned to the position shown in Fig. 5, whereupon said prongs 22-23 begin to bite into the side walls of said groove 15 and the face portion of said tongue 24 rides over the face of the standard by a slight elevation of said fixture, and as the turning operation is continued said tongue 24 slides into groove 15 and permits the close abutment of the face of the base portion 16^a against said face of the standard, said prongs 22-23 being firmly embedded in the walls of said groove, the fixture being in its mounted position as shown in Fig. 6. In view of the beveled arrangement of said tongue 24, but a slight elevation is required to cause the same to ride over the face of the standard, and since the standards themselves are generally made of soft wood, a more or less springy action is present between the same and the piercing parts of the fastening means 19. When the fixtures are removed it is only necessary to slightly elevate the same to remove the tongue from the groove 15, whereupon the said fixture may be turned to free the prongs 22-23 from the side walls of said groove. If desired the shank portion 20 of said fastening means 19 may have its sides notched or corrugated to prevent its pulling out, and in this instance the same may be initially hammered into a fixture instead of threading as previously pointed out.

It will be observed that the fixture shown in Fig. 9 may be artistically configured, while the fixture 18 shown in Fig. 10 has a basal portion 18^a and the inclined tongue previously described in detail.

The panel-supporting members 11 and 12, previously described, may each have their opposite end provided with fastening means 19 for attachment to the standards, as shown in Fig. 11, and in order to permit the insertion and withdrawal of a panel subsequent to the assemblage of said standards and members 11 and 12, said top member 11 is provided with a deep groove 11^a into which the top edge of a panel may be inserted and elevated sufficiently to permit its riding over the top edge of said member 12 for ultimate dropping into the groove 12^a therein. In the removal of a panel the operation is reversed.

As heretofore pointed out the provision of a plurality of grooves permit of various arrangements between a standard and the fixture, and as shown in Fig. 12, the hook members 16 may be placed in a reversed position at the base of a standard for the purpose of providing feet therefor.

Upon reference to Fig. 3, it will be observed that the grooves 15 are provided with inwardly converging side walls, which have a tendency to clamp the edges of a panel for maintenance in a fixed position.

While the present is a disclosure of the preferred embodiment of the invention, it is to be understood that the invention is not limited thereto, as various changes in the minor details of construction, proportion and arrangement of parts may be resorted to without departing from the spirit of the invention as defined in the appended claims.

10 I claim:

1. A fixture adapted to be secured to a supporting member having a longitudinal groove, said fixture having a rearwardly disposed tongue insertible in said groove to prevent lateral displacement of said fixture, and means having a sharpened end adapted to be forced into the rear wall of said groove and having lateral prongs insertible in the side walls of groove upon partial rotation 20 of said fixture.

2. A fixture adapted to be secured to a supporting member having a longitudinal groove, said fixture having a rearwardly disposed tongue, equal in width to said groove and insertible therein, said tongue presenting a beveled outer face to facilitate insertion of said tongue, and means for fastening said fixture to said member, embodying a sharpened end adapted to be forced into the rear wall of said groove and having lateral prongs adapted to enter said groove and upon partial rotation insertible in the side walls thereof.

In testimony whereof I affix my signature.
35 ABRAHAM ASHKENAS.
